EDWARD J. ABBOTT, OF WILTON, NEW HAMPSHIRE.

WINDING MACHINE.

Application filed December 10, 1920. Serial No. 429,695.

This invention relates to textile machines, and especially to winding, doubling, twisting or spinning machines of the type comprising means for winding simultaneously a plurality of wound masses or packages of yarn, thread or other filaments, hereinafter referred to as yarn.

So far as I am aware it has heretofore been the practice when attempting simultaneously to control the winding of a plurality of different packages or masses of yarn to rely upon a fixed operative relation between the winding spindle or carrier for the wound mass, ball, cop or cheese of yarn and the means for driving this winding spindle or carrier, such machines being provided with means for distributing the layers of winding yarn upon the winding package in the desired arrangement.

Such machines typically include the desired plurality of suitable spindles for the carriers, bobbins or supports, if any, for the winding yarn, and means for driving them; suitable guides for the yarn between the unwinding mass and winding mass, and laterally or vertically traversing or otherwise actuated distributing guides for determining the position in the winding layer of the yarn winding upon the rotating winding package.

Such a machine must have driving means operatively positioned in relation to each of a plurality of units each comprising the above mentioned mechanism; and the traversing distributing guides may or may not have common mechanism for governing the simultaneous positioning of the plurality of traversing guides. Typical machines of the class referred to are those employed for winding balls, cops, cheeses, or spools; or spinning machines on which the yarn is wound as it is formed; or doubling machines in which the winding is incidental to disposing side by side, and twisting or untwisting, yarns from pluralities of separate unwinding bobbins or other masses of yarn.

A common defect of winding machines in general use resides in the necessity for circulation about the machine of the operator whose duty it is to replenish the unwinding packages and to remove the wound packages when finished. Attendance upon such a machine involves carrying about the machine of heavy weights of fresh supplies of yarn; and also involves delay in operation due to

the necessity for providing at each winding pair (thereby meaning the unit of unwinding package, winding package, drivers for the winding package, and distributing guides) automatic means for stopping the operation either upon exhaustion of the yarn being wound or completion of the wound mass, until such time as the circulating operator of the machine can finish replenishing the supplies at the intervening stopped units or removing all of the intervening finished and stopped packages. This is wasteful of time and exhausting to the operator. It moreover leads to variable idle time with respect to the capacity of the machine, depending upon the activity and skill of the operator; and in any event it necessitates a cumbersome complexity in the machine in which automatic stop motions at each of the units to determine breakage, knots, slubs, exhaustion of the unwinding mass, and completion of the wound mass must be provided.

So far as I am aware, these defects have not been avoided or palliated in any machine capable of winding cheeses, cops or balls, or, in general, headless packages as distinguished from spools.

A principal object of this invention is to avoid the above difficulties, reduce the labor of attendance and increase efficiency by the provision of a machine for simultaneously winding headless packages, cheeses or balls and unwinding at a desired large number of winding pairs so arranged that a single attendant can take care of a large number of winding pairs without leaving a fixed station, and thereby to avoid the carriage of heavy supply bobbins or heavy finished wound balls, cops, or cheeses from place to place. Another object is to provide for the concomitant operation of and circulation about the machine of winding units comprising an unwinding mass of yarn and a driven carrier for a winding mass of yarn, and distributing guides for the unwinding and winding yarn. Further objects of the invention are to provide in a machine arranged for the circulation about the machine of the winding pairs, common means for driving a plurality of winding pairs and for guiding in relation to the winding mass the yarn being wound; and to provide for continuing the operation of the winding pairs except at a desired predeter-

mined part of the path of circulating travel, at which part the operator is stationed. Other objects are to provide for the above and other purposes a textile machine of the nature mentioned having improved constructions and dispositions of its parts as herein shown and described.

This invention is applicable to and useful in any of the above mentioned machines, but I shall describe it in connection with a particular illustrative species of the genus of my invention, in which species the wound mass is a self-sustaining traverse-wound ball or cheese built up, as usual, of layers of yarn lying in spiral or helical formation, reversals of the direction or pitch occurring at the unsupported faces comprised of the ends of the layers; and suitable for warp for weaving, for direct use in a knitting or other yarn-using machine, or as weft for a continuous-weft loom.

In the accompanying drawings,—

Figure 1 is a side elevation of a machine typical of the invention;

Figure 2 is a plan, parts being broken away;

Figure 3 is an elevation of the right end of Fig. 1; and

Figure 4 is an enlarged detail section on line 4—4 of Fig. 2.

Figure 5 is a fragmentary plan view to enlarged scale illustrating a travelling carrier, employed in the machine, and

Figure 6 is a fragmentary section on line 6—6 illustrating a bearing bracket employed.

The machine comprises end frames 1 and intermediate frames 2, in any desired number, preferably made as shown as castings having suitable seats for upper longitudinal rails 4, 4, and lower longitudinal rails 5, 5. Other longitudinal struts may if desired be provided, for instance as shown at 6, 6, to increase the strength and rigidity of the frame work. A sufficient number of frames 2 will be provided to build a machine of the desired length, which length may be dictated by the length of the unbroken yarn on the unwinding package and the speed of circulation of the winding pairs, as explained below. Whether or not the frames 1 are provided with sufficient longitudinal struts to stand alone without aid from the rails 4 and 5, these rails are bent at 4^a, 5^a, in semi-circular curves about centers preferably within the end frames 1 and near them so as to provide vertically spaced tracks for winding and unwinding package carriers 10 adapted to be circulated about the machine.

Preferably the carriers 10 are constructed as best shown in Figs. 1 and 3, as substantially upright sheet or cast metal plates having attached thereto guide lugs 12 to take over the bottom track 5, and upper guide and driving lugs 13 extending horizontally inward from the upper rear faces of the car-

riers 10 (see Fig. 2). The lugs 13 may be in the form of open rectangular frames, as shown, having spaces therein for antifriction rolls 14 on suitable horizontal journals 17, and adapted to rest on the upper rails 4. Preferably the frames have machined seats on their under faces for guide rolls 15 turning on vertical shoulder screws 16 in the frames 13 and adapted to bear on the respective inner and outer faces of the rail 4. By these expedients the carriers 10 are adapted to move with accuracy of position and little friction completely around the machine as guided by the rails 4 and 5.

In order to move the carriers 10 the rear faces of the frames 13 are provided with vertically bored driving lugs 19 adapted to be suitably connected, as by pins 21, to links 22 at spaced distances of an endless chain 20 adapted to be driven in a path all parts of which are substantially equidistant from the top rail 4. Preferably the driving lug 19 on the frame 13 is placed as shown near the forward edge of the carrier, immediately behind the guide rolls 15, 15, so that the points of attachment of the chain 20 shall not be shifted to different distances from the rail 4 during motion around the ends of the machine, at which times the plates 10 approach successive tangents to the curved portions of their guides.

Any suitable means for driving the chain 20 at the desired speed may be employed. Preferred means illustrated in the drawings comprise sprocket wheels 25 and 26 at the respective ends of the machine respectively mounted on vertical shafts 27 and 28. Shaft 27 may be fixed in a bearing 29 arranged to slide longitudinally with a bracket 30, 31, slotted at 32 for hold-down bolts 33 attaching it to the left hand end-frame. The transverse member 31 may carry the semi-circular segment 4^a of rail 4 at the left end of the machine, a scarf-joint 4^b at each side of the machine maintaining continuity of the track 4 at different longitudinal positions of the bracket 30, 31, shaft 27 and sprocket 25, the motion of these parts permitted by slots 32 serving to permit adjustment to take up slack in chain 20. Shaft 28 is arranged to drive the system comprising wheel 25, the chain 20 and the carriers 10, and for this purpose the sprocket 26 is keyed to it and the shaft is mounted to rotate in bearing lugs 34 and 35 on the left hand face of the end frame 1. Preferably the lug 35 is formed on a horizontal strut 36 and receives a reduced portion 28^a of the shaft 28, which carries a worm gear 37 between the bearing lug 34 and the bearing lug 35. Preferably the hub of the gear 37 rests upon antifriction discs 37^a.

The gear 37 is driven by a worm 38 on a longitudinal shaft 39 in bearing brackets

39^a on strut 36, and 39^b on the frame 2, which shaft is provided with a pulley 40 driven by belt 45 from a smaller pulley 41 on a longitudinal shaft 42 mounted in brackets 43, 44, bridging the sides of the machine at its right hand end. Shaft 42 may be the primary driving shaft, having thereon fast and loose pulleys 46, 47, for the drive belt, and at one end a drive pulley 52 for a belt 53 in turn driving a pulley 54 on a counter-shaft 55 having bearings in the machine frame.

One face of pulley 54 is provided with an eccentric or cam 57 for a follower 58 on a shaft 59, in longitudinal bearings of the machine, for a purpose presently mentioned.

Shaft 42 at the other end carries a spiral pinion 60 meshing with a pinion 61 on a transverse shaft 62 in bearings 63, 63, of bracket 43, and provided with bevel pinions 64, 64, at the respective sides of the machine meshing with similar gears 65, 65, on the projecting reduced ends of rolls 70, 70, having end bearings in the parts 71, 71, of bracket 43.

The rolls 70 are tractor or driving rolls extending the length of the machine and parallel with the track 4 and the straight runs of chain 20. These rolls may be knurled or finely grooved in a longitudinal sense, and may be provided with intermediate bearing grooves 73 to rest in upwardly-open bearing forks 75 mounted at suitable points and overhanging the chains 20, as best shown in Fig. 4. The edges of grooves 73 are preferably beveled off as at 70^a to permit a thread-mass to slide over them without damage.

As best shown in Fig. 1, the semi-circular end 4, the bearings 71 and gears 65, 64, are covered by a semi-circular polished shield 80 of curved cross-section mounted on the bearings 71 and continuing the slideway formed by rolls 70 for a thread mass carried as presently explained by the carriers 10. A similar shield 81, mounted on brackets 82 fast on the opposite frame member 2, which brackets have therein end-bearings for rolls 70, supports the winding thread-masses as they are carried about the left end of the machine as viewed in Figures 1 and 2.

The carriers 10 may comprise an upward and inward extension 90 at each edge of the vertical plates of metal of which said carriers mainly consist, said extensions 90 having vertical grooves 91 for the ends of a winding spindle 92 for a wound-mass core 93, which may be a wooden rod, paper tube or any other form of wound package carrier. The grooves 91 are preferably in the vertical plane of the axes of rolls 70 when the carriers 10 are moving in the longitudinal parts of their path, and the yarn of the yarn mass being wound rests upon the

rolls 70 by gravity and is driven by these rolls with a constant surface velocity.

On each carrier 10 any suitable bobbin holder, such as outwardly projecting brackets 95, support and hold the unwinding bobbins B, or other unwinding member of the winding pair, and the unwinding yarn is carried through a fixed guide 96 to a traversing guide 99 of a quick traverse mechanism preferably having an operating element on the frame, and means for working the guide 99 on each carrier 10.

In the form shown, guide 99 is formed in the forwardly projecting upper end of one arm 101 of a bell-crank lever 101, 102 pivoted at 103 on the back of carrier 10 and having an antifriction roll 104 projecting inwardly from the end of the shorter arm 102 of the bell-crank into engagement with a continuous actuator track or channel 105 above the track 5 having curved ends corresponding to the ends 5^a of track 5, and mounted for oscillatory motion about its longitudinal center.

Preferably rocker frames 107 are fastened on shaft 59 at suitable intervals to support and operate the track 105 according to the motions of shaft 59. These motions are given by an arm 110 fast on shaft 59 and carrying the follower 58 mentioned above. The traverse motions for all the winding masses alike are thus derived from the cam track 57, which may have any desired shape suitable for providing the desired quick traverse for winding the headless yarn mass or cheese in the form of the usual self-sustaining package characterized by layers of yarn laid in reversed spirals or helices of relatively steep or quick pitch, the reversals appearing at and constituting the end faces of the package.

The operation will now be clear. The operator having at hand a supply of bobbins for replenishment sits at the right end of the machine. As the successive carriers 10 reach the shield 80, the rotative motion of the winding pair ceases, and the traverse of guide 99 lessens, ceasing entirely at the longitudinal end of the machine. The length of the machine and the length of the yarn on the bobbins are so related that the supply bobbins B are exhausted when the carriers have made a complete circulation. The operator may now very conveniently doff the exhausted bobbin, place a replenishment bobbin on holder 95, and tie in the fresh end during passage past her of the carriers 10; winding recommences as soon as the cheese or cop on the carrier passes the shield 80.

I claim:

1. A winding machine having therein means for moving a winding mass of yarn in a predetermined path, and means for winding yarn on the mass during such motion to form a traverse-wound self-sustain-

- ing headless package or cheese, by overlapped layers of reversed spiral windings.
2. A winding machine having therein means for winding a traverse-wound headless ball or cheese of yarn or thread and means for moving the winding ball or cheese past a fixed point during winding, the means for winding including means for traversing the yarn on the surface of the winding mass by motions in and opposite to the general direction of motion of the ball or cheese.
3. A winding machine having therein means for circulating a winding mass of yarn in a closed predetermined path, and means acting during such circulation for rotating the winding mass and distributing the yarn upon it in spirals of such traverse and pitch as to form a headless self-sustaining wound package or cheese.
4. A winding machine having therein means for circulating a winding mass of yarn in a closed predetermined path, and means acting during such circulation for rotating the winding mass and distributing the yarn upon it in reversed spirals such as to form a headless self-sustaining wound package or cheese, in combination with means to stop the winding motion at a predetermined point in the path of circulation.
5. A winding machine having therein means for moving a series of winding masses of yarn severally in the general direction of the axes of their winding motion, and successively in a predetermined path, and means for winding yarn on each of the masses during such motion to form a traverse-wound headless package or cheese.
6. A winding machine having therein means for carrying a series of unwinding and winding masses of yarn, means for causing the carriers and packages to traverse a predetermined circulatory path, and winding means active during such motion including a guide acting to lay the yarn on the winding package by motions relative to the winding mass occurring in the general direction of travel of the package in the form of a traverse-wound headless cheese.
7. A winding machine having therein means for carrying a series of unwinding and winding masses of yarn, means for causing the carriers and packages to traverse a predetermined circulatory path, and winding means having a driving element not partaking of the circulatory motion active during such motion to lay the yarn on the winding package in the form of a traverse-wound cheese.
8. A winding machine having therein a carrier for transporting unwinding and winding packages, means for moving the carrier, means for supporting the winding package for rotation about an axis lying substantially in the direction of motion of the carrier, and means supported independently of the carrier adapted to rotate the winding package during motion of the carrier.
9. A winding machine having therein a carrier for transporting unwinding and winding packages, means for moving the carrier in a circulatory path, means for supporting the winding package for rotation about an axis lying substantially in the direction of motion of the carrier, and means adapted to rotate the winding package during motion of the carrier through a predetermined part of said path only.
10. A winding machine having therein a plurality of carriers, means for supporting unwinding and winding packages on said carriers for transport thereby, means to move the carriers and packages in a predetermined path, and rotary means having an axis lying in the direction of a part of said path, and acting during such motion by contact with the surface of successive winding packages to rotate such winding packages.
11. A winding machine having therein a carrier for a yarn mass, means for imparting bodily movement to said carrier and yarn mass, and rotary means immovable in the direction of such bodily movement constructed and arranged to turn said yarn mass about its own axis during the bodily movement of said carrier.
12. A winding machine having therein a carrier for a winding package, means for imparting progressive movement to said carrier in a path substantially axial of the winding motion of said package, and a unidirectionally-movable device supported independently of the carrier and having elements movable in circular paths, said device being constructed and arranged to rotate said package during the progressive movement of said carrier.
13. A winding machine having therein means for supporting a winding package, means for imparting bodily movement to said package along a path lying in an axial plane of said package, and means immovable in the direction of such bodily movement and having elements movable only in planes substantially at right angles to said first named plane for rotating said thread mass during its bodily movement.
14. A winding machine having therein a carrier for a winding unit, said unit comprising an unwinding and a winding package, a guide for the carrier, means for bodily moving said carrier along said guide, and means having elements moving only in paths lying in planes at right angle to the adjacent portion of the path of said unit adapted to contact with and rotate said winding package, said means being operative throughout a major portion of the path

of travel of said unit along said guide, and inoperative to turn said winding package at a predetermined part of said path of travel.

5 15. A winding machine having therein holders for a wound yarn-supply package and a rotary winding package, the axes of said supply and winding yarn packages being substantially at right angles one 10 to the other; means for imparting bodily movement to said winding package in an axial direction, and means fixed as respects such bodily movement for rotating said winding package during such movement.

15 16. A winding machine having therein a carrier for an unwinding supply package and a winding package of yarn or thread, and means to move the carrier in a predetermined path and means adjacent to the path of motion of the carrier but supported independently thereof for rotating the winding package by contact with the surface thereof in such manner that elements 25 of such surface rotate in planes substantially at right angles to the direction of motion of the carrier, and at a constant speed.

20 17. In a textile machine, in combination, means for supporting a winding yarn mass, means for guiding said supporting means for bodily movement in a path lying in a plane of the axis of said yarn mass, and means rotatable about a fixed axis for imparting movement of rotation to said winding 35 yarn mass irrespective of the position of the latter relative to said guide means.

30 18. In combination, in a winding machine, means for supporting a yarn mass for rotation about a substantially horizontal axis, means rotatable about an axis substantially parallel to that of said yarn mass and constructed and arranged to rotate the latter, and means permitting the bodily movement in an axial direction of said yarn 45 mass relatively to said rotating means while maintaining the driving relationship therebetween.

40 19. In a machine for winding yarns, in combination means for supporting a yarn mass for rotation about an axis, means for moving said yarn mass bodily in an axial direction, and frictional means guided by fixed bearings and engageable with the peripheral surface of said yarn mass for rotating the same about its axis, said frictional 55 means being constructed and arranged to maintain driving engagement with said yarn mass while the latter is moved relatively thereto.

50 60 20. In a winding machine, a plurality of winding units each comprising a support for a winding yarn mass, a friction drive element rotatable about a fixed axis for rotating said yarn masses, and means for progressively moving said winding units where-

65 by to bring their respective yarn masses into driving relationship to said drive element.

70 21. A winding machine having therein a traveling winding unit comprising a bobbin holder and a yarn mass holder, means turning in fixed journals and contacting directly with a yarn mass carried by said holder for rotating such yarn mass, and a guide for said unit, the length of said guide and the speed of rotation of such yarn mass being 75 so related that said unit will complete its path of movement along said guide substantially simultaneously with the exhaustion of yarn from a bobbin supported upon said holder.

80 22. In a winding machine, a guide, a winding unit comprising supports for a supply yarn mass and a winding yarn mass, means for moving said unit bodily along said guide, and means turning 85 about an axis substantially parallel to the adjacent portion of the path of said unit for rotating said winding mass, said means being constructed and arranged automatically to discontinue rotating said mass 90 at a predetermined part of the travel of the latter along the guide.

95 23. In a textile machine, in combination, an elongated, rotatable drive roll, means for supporting a yarn mass in position to be driven by contact with the peripheral surface of said roll, and means for moving said supporting means in a path substantially parallel to the axis of said roll while maintaining driving contact between said 100 yarn mass and the surface of said roll.

105 24. In a machine of the class described, a carrier comprising a support for a thread supply mass and supporting means for a winding thread mass, means to move said carrier in a path having a substantially straight part, and a roller and means for rotating the roller in fixed journals about an axis substantially parallel to said part of said path, said roller being constructed and 110 arranged to rotate said winding thread mass by frictional engagement therewith during the movement of said winding unit along said path.

115 25. A winding machine having therein a carrier movable in a horizontal path, a support for a supply bobbin on said carrier, a movable support on said carrier for a winding yarn mass rotatable about a horizontal axis, an elongate roller rotatable about a horizontal axis and engageable under said yarn mass, whereby gravity of the yarn mass holds it in contact with the roller, means for turning said roller, and means for moving said carrier longitudinally thereof.

120 125 26. In a winding machine of the class described, a substantially straight elongate guideway, a carrier for a winding yarn mass and for a supply bobbin movable along the guideway, and an elongate roller arranged 130

substantially parallel to said guideway and in a position to engage the under side of said winding yarn mass whereby to rotate the latter, said roller being provided with a 5 supporting bearing intermediate its length.

27. A winding machine of the class described comprising a guideway, a series of winding units movable in succession therewith, each of said units comprising a support 10 for a rotatable yarn mass, and common means comprising a driven roll for rotating such yarn masses as the units traverse the guide, said roll becoming inoperative at a predetermined part of the path of travel of 15 said units whereby to permit the rotation of such yarn masses successively to cease.

28. A machine of the class described having an endless guideway comprising a pair of substantially parallel and straight members and curved members connecting the ends of said straight members, a carrier movable along said guideway and provided with a support for a winding yarn mass, and means associated with the straight portions only 20 of said guideway for rotating such yarn mass during the travel of said unit along said guide.

29. In a winding machine, in combination, an elongate frame, an endless guideway carried thereby, a winding unit carrier movable along said guideway and comprising a support for an unwinding and a winding thread mass, and a plurality of spaced means for intermittently rotating said thread mass as 30 the winding unit progresses along the guideway.

30. In a machine of the class described in combination, an elongate frame having a pair of straight guide rails secured in parallel relation at its opposite longitudinal sides, curved guide rails at the ends of said frame connecting the straight guide rails whereby to form an endless guideway, a winding unit comprising a support for a 40 winding thread mass movable bodily along said guideway with its axis substantially parallel to the direction of its bodily movement, an endless flexible drive member mounted in the frame and having connection to said unit whereby to move the latter continuously along said guideway, and means arranged at the straight portions only of said guideway for rotating the winding yarn mass carried by said unit during its 45 travel along such straight portions of the guideway.

31. A winding machine having therein a carrier for a rotatable winding package, means to move the carrier, an elongate roll 50 mounted to turn in fixed bearings and having its axis substantially parallel to the direction of motion of the carrier, and means for rotating said roll, whereby to rotate the yarn package upon said carrier by frictional contact therewith, the means for moving 55

said carrier longitudinally of said roll being adapted to maintain the driving relationship between said roll and said yarn mass.

32. In a machine of the class described, an elongate frame having mounted thereon 70 a pair of substantially parallel and straight guide members, curved guide members connecting the ends of said straight members, a plurality of winding units mounted for movement along said guide members, said 75 winding units each comprising a support for a winding yarn mass, and power driven rollers arranged substantially parallel to the straight members of said guide and constructed and arranged to have sliding contact with and thereby to rotate the yarn masses carried upon said winding units.

33. In a machine of the class described an elongate driving drum, means for bodily moving a winding yarn mass longitudinally 85 of said drum while in driving contact therewith, means for supporting said drum at a point intermediate of its length, and means for facilitating the passage of the yarn mass across said bearing point.

34. In a winding machine, in combination, an elongate drum for winding a yarn mass by contact therewith, means for supporting said drum at its opposite ends and a supporting bearing for said drum at an intermediate point, said drum being reduced in diameter for engagement with said latter bearing, and having a beveled surface adjacent said reduced portion.

35. In a machine for winding yarn, in combination an elongate rotating drum for driving a winding yarn mass by contact therewith, means for bodily traversing a winding yarn mass longitudinally of said drum, and a bearing for said drum at a 100 point intermediate of its length, said drum being of reduced diameter for engagement with said bearing and having a beveled surface connecting the outer peripheral surface of the drum with the reduced portion thereof upon that side of the bearing toward which the yarn mass moves.

36. A winding machine having therein a series of carriers each for an unwinding and a winding package, means for traversing the carriers and packages in a path substantially parallel to the axis of the winding package, and means adapted to contact with and drive the surface of the winding package through a predetermined distance during the traverse of the carriers, whereby to wind upon the winding package a predetermined length of yarn or thread during each traverse.

37. A winding machine comprising an 125 endless guideway of elongate form along which a carrier for a supply bobbin and a winding thread mass may be caused to travel, means for moving said unit along said guideway, and a plurality of spaced rolls 130

for rotating the surface of said winding mass through a predetermined number of revolutions, the parts being relatively proportioned so that the supply bobbin will normally be exhausted and ready for replenishment at substantially the same part of the path of travel of said carrier.

38. In a winding machine a guide member, a winding unit movable therealong, 10 said unit comprising supports for a winding yarn mass and a supply bobbin, and a pair of driven rolls associated with said guide constructed and arranged to contact with the surface of said winding yarn mass during the travel of said unit along said guide, the speed of said rolls being such that the supply bobbin is substantially exhausted as said unit completes its path of movement.

39. A winding machine having therein a 20 series of carriers, each for an unwinding and winding package of yarn or thread, means to move the carriers in a predetermined endless path substantially parallel to the axis of the winding package, means 25 adjacent to the path of motion of the carriers for rotating the winding package, and means moving with and on the carriers for traversing the winding yarn.

40. A winding machine having therein a 30 series of carriers, each for an unwinding and winding package of yarn or thread, means to move the carriers in a predetermined endless path, means adjacent to the path of motion of the carriers for rotating the winding package, a guide for the yarn 35 movably mounted on the carrier, and means for positively reciprocating the guide in respect to the winding package at a determinate rate related to the motion of the 40 means for rotating the winding package.

41. A winding machine having therein a 45 series of carriers, each for an unwinding and winding package of yarn or thread, means to move the carriers in a predetermined endless path, means adjacent to the path of motion of the carriers, but not partaking of the movement thereof for 50 rotating the winding package about an axis substantially parallel to the direction of motion of the carrier, a traversing guide for the yarn mounted on the carrier, and means mounted on the machine frame for operating the traversing guide during motion of the carrier.

42. In a winding machine having a series 55 of carriers, adapted to be moved successively through a predetermined path and having means for driving a winding package carried by each carrier, a traversing guide on each carrier, an endless track in contact with means on the carrier for operating the guide, and means for moving the endless track to simultaneously reciprocate the several guide operating means.

43. In a machine of the class described,

an endless guideway comprising substantially parallel straight portions, a series of winding unit carriers movable along said guideway and each provided with a yarn 70 traverse guide, means for moving said carriers along the guideway, and common power actuated means for actuating the traverse guides of all of such units while passing along the straight portions of such guideway.

44. In a machine of the class described in combination an endless guideway, a winding and unwinding package carrier movable thereon, a yarn traverse mechanism having an element on the carrier, and movable, 80 power driven actuating means operative upon said element throughout a portion of the travel of said winding unit along said guideway, said traverse mechanism being constructed and arranged to become inoperative at a predetermined point in the path of travel of said winding unit.

45. In a machine of the class described, in combination, a frame having mounted thereon upper and lower endless guide rails, and a carrier movable along said guide rails, said carrier comprising upper and lower members for engaging said rails respectively, a support above said upper rail for holding a winding yarn mass, a support 90 adjacent said lower rail for a supply bobbin, and an oscillating thread guide for guiding the thread in its passage from the supply bobbin to the winding yarn mass.

46. In a winding machine, in combination, a frame, upper and lower guide rails mounted upon the frame and a winding unit carrier mounted for movement along said rails, said carrier comprising a vertical member having upper and lower brackets 100 extending therefrom, guide rolls carried by said upper bracket for engagement with the upper guide rail, means on the lower bracket for engagement with the lower rail, and means for supporting a winding thread mass 105 and a supply thread mass on the carrier.

47. In a machine of the class described, in combination, guide rails, and a winding unit carrier movable thereon, comprising a plate member having on its inner side 110 brackets for engaging the respective rails, a bracket upon its outer side for supporting a supply bobbin, spaced guides at its upper end for a winding thread mass support, and an oscillating traverse guide member pivoted 115 upon its inner surface.

48. A winding machine having therein a guide member, and a winding unit carrier movable thereon, said winding unit comprising means for supporting a winding thread mass; a bell crank lever on the carrier having one arm adapted to guide the running thread and another arm provided with a projection; an actuator for said projection movable on an axis substantially parallel 125 130

with a portion of said guide-member and in engagement with said projection, and means for oscillating the actuator.

49. In a winding machine of the class described, in combination, an elongate frame, a guide rail extending along said frame at either side thereof, winding units each movable along each of said rails, said winding units each comprising a bell crank lever 10 of which the longer arm serves as a thread guide and the shorter arm of which is provided with a friction roll, an actuator having a track extending along either side of said frame for receiving said friction rolls, 15 an oscillating support for said channel guides, and power driven means for oscillating said support.

50. In combination in a machine of the class described, rotary means for driving a 20 winding package, a traverse guide, elongate actuator members for the traverse guide secured to said shaft to be rocked thereby, an arm fixed on said shaft, and cam means 25 rotating in relation to said rotary means for oscillating said arm whereby alternately to raise and lower said actuator members.

51. In a winding machine, in combination, an elongate frame, a pair of substantially vertical shafts located adjacent to the respective ends of the frame, one of said shafts being adjustable toward and from the other, sprocket wheels carried by the respective shafts, an endless sprocket chain engaging the respective wheels, an endless guideway 35 comprising substantially straight portions, a curved member connecting said straight portions at one end thereof, a second curved member connecting the straight portions of said guideway at the opposite end, one of said curved portions being adjustably connected to the respective straight portions by means of a scarf joint, and yarn winding devices connected to said chain for bodily movement along said guideway.

52. A winding machine having therein a series of carriers for winding pairs, means for circulating the carriers in a path forming a closed figure having one or more straight sides, driving means for the winding member of the winding pair adjacent said straight side or sides, and means permitting the winding member to rest upon said driving means during passage thereabout, in combination with a curved fixed guide surrounding another portion of the path of circulation and adapted to hold the winding member of said pair against rotation during its passage thereof.

53. In combination in a winding machine, 60 straight guide members and curved guide members connecting the ends of said straight members to define a circulatory path, a winding unit carrier movable along said guide members and comprising supports for yarn masses at points above and below said guide

members, means associated with said straight members, for rotating one of said yarn masses as said unit passes along said guide members, and a guide associated with said curved guide members for engaging one of the 70 wound packages on said carrier to prevent its axial rotation during passage thereof.

54. In combination in a winding machine, 75 a pair of yarn mass drive rolls having their ends in spaced relation, a carrier for a winding yarn mass movable longitudinally of said rolls and from one of said rolls to the other whereby to permit said rolls successively to rotate such winding yarn mass, and a stationary member having a smooth 80 outer surface forming a substantial continuation of the peripheral surfaces of said rolls and extending between the ends of the latter, whereby to support said yarn mass during its passage from one of said rolls to 85 the other.

55. A winding machine having an elongated guideway, comprising straight portions and curved portions, rotating traction rolls arranged substantially parallel to said straight portions, a winding unit carrier movable along said guideway and comprising a support for a winding thread mass rotatable by engagement with the surface of said rolls, and a smooth shield member extending from the end of one of said rolls to the end of the other for contact with the wound mass as the latter passes in its travel from one of said rolls to the other.

56. In a winding machine in combination, 100 a plurality of rotatable rolls having their axes in substantially the same plane, a winding unit carrier having thereon a support for a supply bobbin, and a support for a winding threaded mass, means for moving said winding unit longitudinally of said rolls whereby to drive the winding thread mass by contact with the peripheral surfaces of the latter, and a stationary member having a surface forming a substantial continuation of 105 the peripheral surfaces of said rolls and extending between the ends of the same whereby to support such thread mass in its passage from one of said rolls to the other.

57. A winding machine having therein 115 straight guideways and a curved guideway connecting the ends of said straight guideways, a carrier having a support for a supply bobbin and a slideway for a winding yarn mass core near its upper end, means engaging said carrier for moving the same along said guideway, rotatable rolls under the slideway and adjacent the straight portions of said guideway for contacting with, supporting and driving the winding thread mass to rotate the same, and a guard member extending along the curved portion of said guideway and forming a substantial continuation of the contact surfaces of the respective rolls.

58. In combination in a machine for winding yarn, an endless guideway comprising substantially straight portions and curved portions connecting said straight portions, a winding unit movable along said guideway, said winding unit comprising spaced supports for a winding thread mass and a supply thread mass, mechanism for moving said winding unit continuously along said guideway, and means associated with the curved portions of said guideway for guarding the yarn from contact with said actuating mechanism.

59. In a winding machine, means for winding traverse-wound cheeses or balls comprising a tractor roll, means for driving it, and a carrier adapted to support laterally a core for a cheese or ball above the

rolls, while permitting the growing cheese or ball to rest on the tractor roll, means on the carrier to supply yarn to the cheese, a traverse guide on the carrier, and means for removing the carrier lengthwise of the roll, and for actuating the traverse guide.

60. A carrier for movable-winding-unit winding machines comprising a support for an unwinding yarn mass, a lateral support for a winding yarn mass offset from one face of the carrier to overhang driving means, and means for rotating the winding yarn mass on the carrier beneath said lateral support.

Signed by me at Boston, Massachusetts, this thirtieth day of November, 1920.

EDWARD J. ABBOTT.
